EXPRESSION DEVICE FOR AUTOMATIC MUSICAL INSTRUMENTS

Original Filed Feb. 4, 1916 3 Sheets-Sheet 3

THOMAS DANQUARD
By Southgate & Southgate Attorneys

UNITED STATES PATENT OFFICE.

THOMAS DANQUARD, OF NEW YORK, N. Y., ASSIGNEE TO AUTO PNEUMATIC ACTION COMPANY, OF NEW YORK, N. Y., A CORPORATION OF NEW YORK.

EXPRESSION DEVICE FOR AUTOMATIC MUSICAL INSTRUMENTS.

Original application filed February 4, 1916, Serial No. 76,077. Renewed July 19, 1921, Serial No. 485,849.
Divided and this application filed March 21, 1922, Serial No. 545,593.

This invention relates to an expression device for automatic musical instruments, of the type in which a tracker bar and perforated note-sheet are used and is a division 5 of my renewal application, 485,849, filed July 19, 1921, of my original application 76,077, filed February 4, 1916, and Patent No. 1,413,832 issued April 25, 1922.

It has been found desirable in the use and 10 operation of automatic musical instruments and particularly of player pianos, to provide automatic means by which the intensity of tone or musical expression of the instrument may be varied. When such means 15 are provided, it is found possible to reproduce the rendition of a particular musical composition, as played by a great artist, so accurately that the reproduced playing of the composition can hardly be distinguished 20 from that of the original performer.

It is the general object of my invention to provide an improved tension regulator of this type, by which the air tension on the 25 player actions in an automatic musical instrument may be varied automatically, and also to provide improved means for controlling such a regulator from special openings in the note-sheet.

One important feature of my invention 30 relates to the provision of improved devices for retaining the tension regulator in adjusted position, thereby avoiding the use of long perforations or slots in the note-sheet, and to the provision of means for 35 automatically releasing said devices prior to or coincident with the adjustment of the tension regulator to a different position.

Further features of my invention relate 40 to certain arrangements and combinations of parts which will be hereinafter described and more particularly pointed out in the appended claims.

A preferred form of my invention is shown in the drawings in which—

Fig. 1 is a diagrammatic elevation of my 45 improved expression device and certain parts of the instrument associated therewith;

Fig. 2 is a vertical sectional view of the 50 tension regulator, taken along the line 2—2 in Fig. 3;

Fig. 3 is a longitudinal sectional view of the tension regulator, taken along the line 3—3 in Fig. 2;

Fig. 4 is a plan view of the setting device which controls the tension regulator;

Fig. 5 is a longitudinal sectional elevation thereof, taken on the line 5—5 of Fig. 4; and

Figs. 6 and 7 are transverse sectional elevations taken on the lines 6—6 and 7—7 of Fig. 4, respectively.

In Fig. 1, I have shown the general relative position of the several parts of my invention, the tension regulator being designated as a whole by the letter R, the setting device by the letter S and the tracker bar by the letter T.

The tension regulator shown in the drawings is of the general type shown and fully described in my prior Patent No. 1,287,649 issued December 17, 1918. This combination regulator controls the air tension on a plurality of pneumatic player actions by which the keys or hammers of a piano are 75 operated. These player actions form no part of my present invention and may be of any usual type such as is shown for instance in Figs. 2 and 3 of the prior patent to Brown, No. 1,011,567, issued December 80 12, 1911. In the form shown in my prior patent, however, no provision is made for automatic setting of the tension regulator and the provision of such automatic setting devices in an improved form constitutes a 85 very important feature of my present invention.

Referring to Figs. 2 and 3, I have shown a box or casing 10, divided by a partition 11 into two air chambers 12 and 13. The 90 chamber 13 is directly connected by a passage 15 and pipe 15^a to the exhaust of the instrument, while the chamber 12 is provided with a passage 14 which forms an inlet for the pipe 14^a leading from the pneumatics which operate the actions of the instrument. The chambers 12 and 13 are connected by a port 16 extending through the partition 11 and normally open as shown in Fig. 2.

A tension valve 17 is pivoted at 18 to the 95 partition 11 and is adapted to be swung

across the port 16, thereby closing the passage between the chambers 12 and 13 to a greater or less extent, and correspondingly decreasing or increasing the air tension in the 5 chamber 12. The tension valve 17 is adjustably connected by a link 20 to a cross-bar 21 which is rigidly secured to the movable leaves of three pneumatic bellows 22, 23 and 24, mounted in fixed relation to the 10 casing 10 and collectively constituting what may be termed a "pneumatic motor" for selectively positioning the valve 17. The movable leaves of the three bellows and the crossbar 21 carried thereby are normally 15 maintained in raised position by a spring 25 mounted upon arms 26 and 27 secured respectively to the movable and to the fixed leaves of the bellows.

The low tension chamber 12 is connected by 20 a passage 30 to a second low tension chamber 31 formed in a casing 32 secured to and rigidly connecting the fixed leaves of the bellows 22, 23 and 24. In the side wall 32^a of the casing 32, a series of valve chambers 25 33, 34 and 35 are provided, each of these chambers being directly connected to the interior of one of the bellows 22, 23 and 24. A passage 33^a connects the valve chamber 33 to the bellows 22 (Fig. 2) and similar 30 passages, not shown, connect the valve chambers 34 and 35 to the bellows 23 and 24 respectively.

The valve chamber 33 is provided with two ports 33^b and 33^c, the port 33^b being 35 open to the atmosphere and the port 33^c communicating with the low tension chamber 31. The latter port is formed in a cup-like member 36 secured to the frame member 32^a and forming the inner side of the 40 valve chamber. A double valve 37 is mounted to slide axially in said chamber and to close one or the other of said ports, according to its position.

The valve 37 is provided with a head 38 45 positioned for engagement with a diaphragm 39 forming a so-called pouch and covering a recess 40 formed in the wall 32^b of the casing 32. A pipe or tube 41 leads from the recess 40 and is connected at its 50 opposite end with a setting device to be hereinafter described. For the present it is merely necessary to state that the setting device comprises means for normally closing the tube 41 and for opening the same 55 to the atmosphere under predetermined conditions.

A bleed opening 42 connects the recess 40 to the low tension chamber 31, thus normally maintaining equal low tension upon 60 both sides of the diaphragm 39. The valve chambers 34 and 35 are provided with valves, pouches, and controlling tubes precisely similar in construction and operation to those just described and a detailed description thereof is considered unnecessary. 65

The tube which controls the valve mounted in the chamber 34 is marked 43 and the corresponding tube for the chamber 35 is marked 44.

As above stated, the tubes 41, 43 and 44 70 are normally closed and the bleed openings maintain equal low tension upon both sides of the diaphragms controlled thereby, the diaphragms being thus rendered inactive. The low tension in the chamber 31 normally 75 draws the double valve 37 against the port 33^b in the cap 36, thus closing communication between the valve chamber 33 and the low tension chamber 31. At the same time the uncovering of the port 33^b 80 opens the valve chamber to the atmosphere. The valves in the chambers 34 and 35 are similarly arranged and positioned. Each bellows 22, 23 and 24 is thus exposed to atmospheric pressure within and without and the movable leaves will be raised by the 85 spring 25.

Assuming now that the setting device 90 opens the tube 41 to the atmosphere, the diaphragm 39 will then be exposed to atmospheric pressure upon its right-hand side and to low tension or exhaust pressure upon its left-hand side, as viewed in Fig. 2. The diaphragm will consequently move inward, engaging the head 38 of the valve 37 95 and moving the valve to open the port 33^b and to close the port 33^c.

The bellows 22 is thus connected through the passage 33^a and the valve chamber 33 to the low tension chamber 31, causing deflation of the bellows 22 to a certain extent 100 against the tension of the spring 25. The movable leaves of the bellows and the cross-bar 21 carried thereby will thus be moved downward a certain distance, thereby swinging the valve 17 to partially close the port 16 and decrease the tension in the chamber 12. The tension thus obtained may be designated "F", full tension being 110 indicated by "FF".

If the tube 43 is thereafter opened, the bellows 23 will be connected to the low tension chamber 31 and the movable leaves of the bellows will be moved further downward by the increased relative pressure thereon, thus moving the valve 17 to cover an additional portion of the port 16 and produce a soft tension designated "P". If the tube 44 is thereafter opened the bellows 24 will become operative and the valve 17 will be swung still further downward to more completely close the port 16, giving a very soft or "PP" effect.

In Figs. 4, 5, 6 and 7, I have shown a 125 form of setting mechanism through which the tension regulating bellows 22, 23 and 24 may be controlled from the openings in the tracker bar. Considering the control of the bellows 22, the tube 41 (Figs. 2 and 3) is connected to a passage 110 (Fig. 6) 130

formed in a frame 111 and communicating with a cross passage 112. At its upper end the cross passage is open to the atmosphere and at its lower end it is open to an exhaust chamber 113 connected by a pipe 113^a (Fig. 7) to the exhaust of the instrument. A double valve 114 is mounted to slide loosely lengthwise of the cross passage 112, closing the passage at one end or the other according to conditions. At its lower end the valve 114 is provided with a head 114^a positioned for engagement by a diaphragm 115 covering a recess 116, connected by a passage 117 to the tube 62 extending to the opening 63 (Fig. 1) in the tracker bar. The usual bleed opening 119 (Fig. 5) connects the recess 116 with the chamber 113 thus providing a normally low pressure on each side of the diaphragm 115. The passage 110 above referred to is provided with an extension 110^a containing a flap valve 120 and communicating with a cross passage 121 (Fig. 4).

Substantially similar valve mechanism is provided for controlling the admission of air through the passages 122 and 123 to the tubes 43 and 44 through which the bellows 23 and 24 are governed, these mechanisms being connected by tubes 84 and 85 to tracker openings 86 and 87 and being also connected to the cross passage 121.

Referring to Fig. 6, the valve 114 is connected at its upper end to a lever 130 having its outer end positioned for engagement by a pawl 131 adapted to retain the valve in raised position.

From the foregoing description the operation of this portion of the mechanism will be clearly evident. When a perforation in the note sheet admits atmospheric pressure through the tube 62 and passage 117 to the recess 116 the diaphragm 115 will be raised, carrying with it the valve 114, thus closing the connection between the passage 110 and the exhaust chamber 113, and at the same time opening the passage 110 to the atmosphere. Since the passage 110 communicates directly with the tube 41, atmospheric pressure will accordingly be transmitted through the tube 41 to the recess 40, thus rendering operative the bellows 22.

At the same time atmospheric pressure will be transmitted through the passage extension 110^a to the cross passage 121. This passage 121 communicates by a transverse passage 132 (Fig. 7) with a recess 133, covered by a diaphragm 134, which controls the release valve 135. The valve 135 is pivotally connected to a lever 136 having a depending latch 137 positioned to engage an arm 138^a fixed to an offset bar 138 (Fig. 4) pivotally supported in bearings 139 secured to the frame 111. The offset portion of the bar extends lengthwise

of the device and engages projecting portions 131^a of the pawls 131. Such engagement by the bar 138 moves the pawls 131 rearwardly and permits the levers 130 and the valves 114 connected thereto to return to normal or lowered position.

The latch 137 (Fig. 7) is provided with a laterally extending arm 137^a positioned to engage an adjustable stop 140 as the lever 136 is raised. The stop 140 should be so adjusted that the arm 137^a will engage the stop as soon as the levers 130 have been released. Continued upward movement of the lever 136 will swing the latch 137 to the right (Fig. 7) thus releasing the offset bar 138 and permitting the pawls 131 to return to positions in which they again cooperate with the levers 130. The release valve 135 may also be operated directly from the opening 77 (Fig. 1) in the tracker bar, being connected thereto by the tube 76 as in the preferred form.

As the valves which control the bellows 22, 23 and 24 are each connected to the cross passage 121, the release valve 135 will be operated whenever any one of the expression valves is moved from normal position.

In order that the operation of two or three of the bellows 22, 23 and 24 may be controlled by a single perforation in the note sheet I have provided additional cross passages, most clearly shown in Fig. 5. A passage 150 is normally closed by the valve 151 and when opened admits atmospheric pressure directly to the passage 110, at the same time that atmospheric pressure is admitted to the passage 122. A similar passage 152 normally covered by the valve 153 when opened admits atmospheric pressure to the tube 122. The valve 153 also covers an additional passage 154 connecting into the passage 150 and thus adapted to admit atmospheric pressure to the tube 110. The raising or opening of the valve 151 thus admits atmospheric pressure to the two bellows 22 and 23 while the raising of the valve 153 admits atmospheric pressure to all three of the bellows 22, 23 and 24.

Having thus described one form of my invention it will be seen that I have provided tension controlling mechanism by which a series of different tensions may be secured and that I have also provided improved automatic devices controlled by perforations in the note sheet by means of which any desired tension may be secured. Furthermore any desired tension may be at any time secured by the provision of a suitable single perforation in the note sheet regardless of the tension previously maintained in the instrument.

It will also be evident that changes and modifications can be made in my invention by those skilled in the art without departing from the spirit and scope thereof as set forth

in the claims, and I do not wish to be otherwise limited to the details herein disclosed.

What I do claim is:—

1. In an expression device for an automatic musical instrument having a tracker bar and note sheet, a plurality of player actions and an air tension regulator therefor, in combination, a plurality of pneumatic actuators controlling a single air tension regulator and devices for governing the exhaust of air in said pneumatic actuators, said devices comprising a separate valve controlling the operation of each actuator, separate mechanical means effective to positively lock each of said valves in position to render said actuator operative, and a mechanical release device separately controlled from the tracker bar and effective to remove all of said locking devices and thereby unlock all of said valves and permit all of said valves to return to normal position, rendering all of said actuators again inoperative.

2. An expression device for automatic musical instruments having a tracker bar and note sheet, comprising an air tension regulator, a pneumatic motor connected to adjust said regulator and having a plurality of separate pneumatic actuators therein, a separate valve for controlling the operation of each actuator, said valves being controlled from separate openings in the tracker bar, a latch to hold each valve when moved to render an actuator operative, and a single additional sheet-controlled valve effective to move all of said latches to release the valves held thereby.

3. In an expression device for an automatic musical instrument having a tracker bar and note sheet, a plurality of player actions and an air tension regulator therefor, in combination, a plurality of regulator-controlling pneumatic actuators, and devices for governing the exhaust of air in said pneumatic actuators, said devices comprising connections to each actuator, valves for opening and closing said connections to the atmosphere, levers connected to said valves, latches for said levers effective to hold said valves open, and a single release device for all of said latches controlled from a single separate tracker opening.

4. In an expression device for an automatic musical instrument having a tracker bar and note sheet, a plurality of player actions and an air tension regulator therefor, in combination, a plurality of regulator-controlling pneumatic actuators, and devices for governing the exhaust of air in said pneumatic actuators, said devices comprising connections to said actuators, valves for opening and closing said connections to the atmosphere, levers connected to said valves, latches for said levers effective to hold said valves open, and a single release device for all of said latches controlled from a single

separate tracker opening, said release device being also rendered operative whenever any one of said valves is opened.

5. In an expression device for an automatic musical instrument having a tracker bar and note sheet, a plurality of player actions and an air tension regulator therefor, in combination, a plurality of regulator-controlling pneumatic actuators, and devices for governing the exhaust of air in said pneumatic actuators, said devices comprising connections to said actuators, valves for opening and closing said connections to the atmosphere, levers connected to said valves, latches for said levers effective to hold said valves open, a single release device for all of said latches controlled from a single separate tracker opening, and a trip for said releasing device effective to disengage said release device at a selected point in its operative movement.

6. An expression device for automatic musical instruments having a tracker bar and note sheet, comprising an air tension regulator, a pneumatic motor connected to adjust said regulator and having a plurality of separate pneumatic actuators therein, and devices for controlling the operation of said actuators, said devices including a sheet-controlled valve for governing the exhaust of air in each of said actuators, and connections between said valves whereby a certain valve when moved will cause the air to be exhausted in more than one actuator.

7. An expression device for automatic musical instruments having a tracker bar and note sheet, comprising an air tension regulator, a pneumatic motor connected to adjust said regulator and having a plurality of separate pneumatic actuators therein, and devices for controlling the operation of said actuators, said devices including a series of sheet-controlled valves for governing the exhaust of air in each of said actuators, and cross passages between said valves, whereby a certain valve when moved will cause the air to be exhausted in more than one actuator, thereby rendering a plurality of actuators operative.

8. An expression device for automatic musical instruments having a tracker bar and note sheet, comprising an air tension regulator, a pneumatic motor connected to adjust said regulator and having a plurality of separate pneumatic actuators therein, and devices for controlling the operation of said actuators, said devices including a series of sheet-controlled valves for governing the exhaust of air in each of said actuators, and connections between said valves, whereby a certain valve when moved will cause the air to be exhausted in more than one actuator while the valves normally controlling the additional actuators remain in normal position.

9. An expression device for automatic musical instruments having a tracker bar and note sheet, comprising an air tension regulator, a pneumatic motor connected to adjust said regulator and having a plurality of separate pneumatic actuators therein, a separate valve for controlling the operation of each actuator, said valves being controlled from separate openings in the tracker bar, and connections between said valves whereby certain tracker openings are rendered effective to control a plurality of pneumatic actuators.
10. In an expression device for an automatic musical instrument having a tracker bar and note sheet, a plurality of player actions and an air tension regulator therefor, in combination, a plurality of regulator-controlling pneumatic actuators, and devices for governing the exhaust of air in said pneumatic actuators, said devices comprising a valve connected to control each actuator, sheet-controlled means to move each valve to render its actuator operative, additional mechanical means to positively retain said valves when thus moved, an additional sheet-controlled release valve, and a mechanical release device by which all of said actuator-controlling valves are simultaneously released when said release valve is operated.
11. In an expression device for an automatic musical instrument having a tracker bar and note sheet, a plurality of player ac-
- tions and an air tension regulator therefor, in combination, a plurality of regulator-controlling pneumatic actuators, and devices for governing the exhaust of air in said pneumatic actuator, said devices comprising valves covering ports connected to control each actuator, sheet-controlled means to move each valve to render its actuator operative, certain of said valves covering additional ports, and connections from said additional ports whereby actuators associated with other valves are rendered operative when said ports are uncovered.
12. In an expression device for an automatic musical instrument having a tracker bar and note sheet, a plurality of player actions and an air tension regulator therefor, in combination, a plurality of regulator-controlling pneumatic actuators, and a device for governing the exhaust of air in said pneumatic actuator, said devices comprising a valve connected to control each actuator, sheet-controlled means to move each valve to render its actuator operative, a retaining device for each valve, a release valve controlling all of said retaining devices, and a connection from each actuator-controlling valve to said release valve, whereby movement of any controlling valve from normal position actuates said release valve.

In testimony whereof I have hereunto affixed my signature.

THOMAS DANQUARD.
